UNITED STATES PATENT OFFICE.

JACOB HESSLER, OF CHICAGO, ILLINOIS.

CABINET-ORGAN.

SPECIFICATION forming part of Letters Patent No. 352,128, dated November 9, 1886.

Application filed June 9, 1884. Serial No. 133,551. (No model.)

To all whom it may concern:

Be it known that I, JACOB HESSLER, a citizen of the United States, residing in Chicago, in the county of Cook and State of Illinois, have 5 invented a new and useful Improvement in Cabinet-Organ, of which the following is a specification.

This invention relates to that class of cabinet-organs which are provided with a sliding 10 lid, connected with a swell by devices substantially as herein shown and described.

In the accompanying drawings, which form a part of this specification, and in which similar letters of reference indicate like parts, Fig. 15 Fig. 1 is a transverse vertical section of an instrument embodying my invention. Figs. 2 and 3 are similar views showing different forms of devices whereby the swell is operated, and Fig. 4 is a horizontal section of the 20 form shown in Fig. 3.

In the drawings, A represents the top, A' the front, A² the lid, A⁴ the end, and A³ the back, of the case of a cabinet-organ. In the back, near the upper part of the case, is an 25 upright hinged valve, B. The said valve B is opened when the organ-lid A' is opened, and remains so while the instrument is being played. In the drawings I have illustrated a number of ways in which it may be operated.

In all of the modifications I have shown the lid as being attached to a swinging frame, C, upon which its inner edge is supported.

In Fig. 1 a toggle-connection, d d, connects 35 the swinging frame or the lid with the upper edge of the swell-valve, the opening of the lid in this case serving to allow the top of the valve to open also, a hook, d', or equivalent device 40 acting to prevent the valve from opening too far. When the lid is closed, it straightens the toggle and shuts the valve.

In Fig. 2 a straight wire, e, connects the up-

per part of the swell with the swinging frame C, at about the middle of the latter. This insures the opening of the valve with the opening of the lid, and the closing of both simultaneously, also, the open position being indicated by broken lines.

In Fig. 3 the valve is opened by the opening of the lid, and is connected thereto as follows: A longitudinal and horizontal lever, h, is stationarily pivoted at one end by the pivot h', and its opposite end is connected to the lid or swinging frame C by the link h². The link or wire h³, attached to said lever at a point substantially midway between its ends, extends to the valve, as shown. This construction results in the opening or closing of the lid and valve simultaneously whenever the former is moved.

It will be noticed that in all the modifications where the valve is operated by the lid a differential movement is imparted to the valve from that required by the lid. This, however, is a matter of discretion.

I claim—

1. The combination, in a cabinet-organ, of the sliding lid A², the valve B, and the devices connecting said lid and valve, substantially as specified.

2. In a cabinet-organ, the lid and its swinging frame C, in combination with the valve B and the devices connecting said frame to the valve, substantially as specified.

3. In a cabinet-organ, the combination, with 75 a vertical swell-valve, B, of devices for opening and closing the same and the hook d', for limiting the opening movement, substantially as specified.

JACOB HESSLER.
